AUTOMATED COOKING UNIT

Jerry J. Oxford, Granite City, and Donald M. Kaffer, Belleville, Ill., and Leo M. Stremfel, Florissant, Mo., assignors to Oxford Manufacturing Company, Belleville, Ill., a corporation of Delaware

Filed June 10, 1968, Ser. No. 12,289

Term of patent 14 years

Int. Cl. D7—04

U.S. Cl. D81—10

FIG. 2

FIG. 1

FIG. 3

FIG. 1 is a perspective view of an automated cooking unit showing our new design,

FIG. 2 is a right side elevational view thereof,

FIG. 3 is a front elevational view of a modification of our design, and the right side elevational view of the modification shown in FIG. 3 is similar to the left side of the modification of FIGS. 1 and 2 and the left side of the modification of FIG. 3 is similar to the right side of the automated cooking unit shown in FIGS. 1 and 2.

The essential features of our design reside in the portions shown in solid lines.

We claim:

The ornamental design for an automated cooking unit, substantially as shown and described.
